UNITED STATES PATENT OFFICE.

JULIUS F. ADAMS, OF PITTSBURGH, PENNSYLVANIA; ANNA ADAMS LAUER ADMINISTRATRIX OF SAID JULIUS F. ADAMS, DECEASED.

DESIGN FOR A GAS HEATER.

Application filed June 3, 1925. Serial No. 13,643. Term of patent 3½ years.

To all whom it may concern:

Be it known that I, JULIUS F. ADAMS, a citizen of the United States, residing at Pittsburgh, in the county of Allegheny and State of Pennsylvania, have invented a new, original, and ornamental Design for Gas Heaters, of which the following is a specification, reference being had to the accompanying drawings, forming part thereof.

Fig. 1 represents a front view of a gas heater showing my new design, and Fig. 2 is a side view thereof.

I claim:

The ornamental design for a gas heater as shown.

JULIUS F. ADAMS.
